United States Patent Office

Des. 206,367
Patented Nov. 29, 1966

206,367

NON-WOVEN TEXTILE FABRIC

George H. Hughes, Granby, Quebec, Canada, assignor to
Beacon Manufacturing Company, Swannanoa, N.C., a
corporation of Delaware

Filed Aug. 5, 1965, Ser. No. 86,449

Term of patent 14 years

(Cl. D92—1)

FIG-3FIG-4

FIGURE 1 is a scale-wise perspective view of one face of a non-woven textile fabric showing my new design;

FIGURE 2 is a scale-wise perspective view of the opposite face of that shown in FIGURE 1;

FIGURE 3 is an enlarged fragmentary perspective view of the design as shown in FIGURE 1; and

FIGURE 4 is an enlarged fragmentary perspective view of the design as shown in FIGURE 2.

I claim:

The ornamental design for a non-woven textile fabric, as shown.
